UNITED STATES PATENT OFFICE.

WILLIAM SALLADE, OF PHILADELPHIA, PENNSYLVANIA.

LATCH.

SPECIFICATION forming part of Letters Patent No 291,539, dated January 8, 1884.

Application filed January 9, 1883. (No model.)

To all whom it may concern:

Be it known that I, WILLIAM SALLADE, a citizen of the United States, residing at Philadelphia, in the county of Philadelphia and 5 State of Pennsylvania, have invented a new and useful Improvement in Fastenings for Doors, &c., of which the following is a specification.

My invention relates to a locking device in 10 which the latch, bolt, or bar is operated by a jointed hasp, serving for a handle or lever.

In the accompanying drawings, Figure 1 shows a front elevation; Fig. 2, a back elevation; Fig. 3, a back elevation, a bar being 15 shown in place of a latch; and Fig. 4 is a perspective view of a jointed hasp in connection with its stud and latch or bolt.

Similar letters refer to similar parts in the several views.

20 A is a jointed hasp, the stud B of which extends within or through the door C, and has a bolt, latch, or bar, D, at its inner end. The

hasp is in this instance hinged at a, though it can be a swivel or other joint, so as to be easily bent, as shown at Fig. 4, to serve for a handle 25 or lever for working the latch.

E is a staple over which the end of the hasp takes, and is secured by a lock, F.

It will be obvious that the hasp A, by bending, Fig. 4, after the removal of the lock F, 30 will become a lever or handle, the motion of which will be transmitted by the stud B to the latch, bar, or bolt D for opening the door C.

I claim as my invention—

In a door-latch, the combination of the latch 35 D upon the inside of the door, provided with the spindle B, for connecting said latch with the hinged hasp A upon the outside of the door, and the staple E and suitable lock, F, substantially as and for the purpose set forth. 40

WILLIAM SALLADE.
